WEIGHTING MEANS FOR THE DRAFTING
ROLLERS IN PREPARATORY AND SPIN-
NING MACHINES

Joseph Noguera, Salford, Manchester, England

Application August 2, 1950, Serial No. 177,194
In Great Britain October 21, 1949

7 Claims. (Cl. 19—135)

1

This invention relates to weighting means for the drafting rollers in preparatory and spinning machines, the weighting means being of the kind in which the reassertive force of a coil spring under compression is arranged to exert a downward pull on a saddle assembly bearing on the top roller or rollers of the roller pairs. Weighting means of this kind have already been proposed in which the spring is arranged to bear on a plunger member within a casing, which latter may be held against axial displacement relatively to the machine, the plunger member being connected to a weight transmitting member which extends axially through the spring and casing for connection with a weighting hook or other member of the saddle assembly at the end remote from the plunger. The weight transmitting member is generally guided at a point or points between the plunger member and the end connected to the weighting hook or other member of the saddle assembly so as substantially to prevent its lateral displacement relatively to the machine.

This known arrangement has been found, however, to suffer from the disadvantage that the spring does not always respond sufficiently quickly to the small vertical movements of the saddle assembly which occur during operation, with the result that the weighting pressure on the fibres being drawn is not always sufficiently even and continuous to meet the very exacting requirements of the operation. This slight time lag in the action or reaction of the spring is due mainly to friction which results from the comparative rigidity of the arrangement and which is caused by the spring and/or plunger becoming laterally displaced, or inclined from the vertical, so that one or both of the members, and/or the weight transmitting member tends or tend to rub against the casing, guides or other adjacent fixed parts of the machine.

The present invention is concerned with overcoming the aforementioned disadvantage.

According to the invention there is provided a spring weighting device for use in weighting means of the kind specified wherein a casing having an open mouth at one end and guide means provided at the opposite end is arranged to contain a coil spring which bears between the said open-mouthed end and a plunger member within the casing, and wherein a weight transmitting member is connected to the plunger member and extends axially therethrough so as to project at each end respectively through the mouth and guide means of the casing, the arrangement being

2

such that the end of the weight transmitting member which projects through the mouth and is intended for connection to the weighting hook or other member of the saddle assembly is permitted considerable free lateral movement to allow for operational requirements whilst the possible lateral movement of the opposite end of the said weight transmitting member is limited by the guide means to an amount which is substantially equal to that necessary to permit the said first-mentioned lateral movement, whereby the plunger member and springs are prevented from making any frictional contact with the sides of said casing under normal operating conditions.

15 Due to the positioning of the guide means below the plunger, the friction between the guide means and weight transmitting member is extremely small. The lateral thrust exerted by the weight transmitting member against the guide means

20 is, in fact, considerably smaller than would result if the guide means were located anywhere between the plunger and that end of the weight transmitting member which is intended for connection to the weighting hook or other member

25 of the saddle assembly. The speed of reaction of the spring when it is required to expand or contract due to vertical movements of the saddle assembly is thus greatly increased and considerably more even and continuous weighting of the rollers than has hitherto been possible with this kind of weighting means is achieved.

In order that the invention may be clearly understood one embodiment thereof will now be described in detail with reference to the accompanying drawings wherein—

35 Figure 1 is a side elevation showing a spring weighting device according to the invention in position under a roller beam, which latter is in section and partially broken away, the casing of the device being shown in an open position in chain-dotted lines.

Figure 2 is a sectional side elevation taken in a direction at right angles to Figure 1, the roller beam section being omitted, and

40 Figure 3 is a plan view of the device according to Figure 1 the roller beam section again being omitted.

Referring now to the drawings, a cylindrical casing 1 is slit down each side as at 2 to form two part-cylindrical portions and is partially closed at the lower end by means of a transverse bridge member 3 formed with a central guide slot. At the opposite end, the casing 1 is provided with an inwardly directed annular rim 4 having inwardly extending projections 4a at intervals

therearound, the inner marginal edge 4b of each said projection 4a being downturned so as to lie substantially parallel to the longitudinal axis through the centre of the casing 1 for a purpose which will be plain from the following description. Within the casing 1 there is arranged a coil spring 5 under compression between a plunger member 6, which is adapted normally to rest on the aforesaid bridge member 3, and a bearing plate 7. The bearing plate 7 has a central aperture 8 therethrough surrounded by an upstanding annular boss 9, and is formed with an annular groove 10 in the upper surface around the boss 9, in which groove the downturned portions 4b of the rim 4 can engage to hold the said two parts of the casing 1 together as shown in full lines in Figure 1. In this operative position of the bearing plate 7 the annular boss 9 projects through the adjacent end of the casing and the aperture 8 which it surrounds forms an open mouth for the casing.

Extending axially through the mouth 8, the spring 5, the plunger 6 and the aforesaid slot in the bridge member 3 is a weight transmitting member 11 in the form of a flat elongated metal strip fixedly connected approximately in the middle to the plunger 6 and having a hooked portion 11a at one end which projects through the mouth 8 for connection to part of a link or lever system 12 which in turn forms part of the saddle assembly. The opposite end 11b of the member is plain and projects through the guide slot in the transverse bridge member 3.

In this example the casing 1 is shown as positioned below a roller beam 13, the boss 9 on the bearing plate 7 being seated in an aperture 14 which is formed to receive it in the beam and through which the hooked end 11a of the weight transmitting member 11 projects. The mouth 8 as defined by the annular boss in the bearing plate 7 and the aperture 14 in the roller beam are of sufficient size to allow the hooked end 11a of the member 11 considerable free lateral play such as will be sufficient to meet operational requirements. The slot in the bridge portion 3 on the other hand is of such size as to allow very limited lateral movement of the end 11b of the weight transmitting member 11, the lateral movement between the weight transmitting member and the aforesaid slot being in fact limited to that which is substantially sufficient to allow the lateral play between the hooked end 11a of the weight transmitting member and the outlet mouth 8 of the casing. In this way, under all normal operational conditions, the plunger 6 and spring 5 are prevented from making contact with the side walls of the casing 1 whilst the friction between the weight transmitting member 11 and the guide slot in the member 3 is extremely small due to the fact that the guide is positioned below the plunger. With this positioning of the said guide, the lateral thrust exerted by the weight transmitting member 11 on the edges of the guide slot is, in fact, considerably smaller than would result if the guide were located anywhere between the plunger 6 and the hooked end 11a of the weight transmitting member and the speed of reaction of the spring 5 is thereby greatly increased.

I claim:

1. A spring weighting device for the drafting rollers in preparatory and spinning machines comprising a casing having an open mouth at one end and guide means at the opposite end, a plunger arranged loosely within said casing, a

coil spring bearing between said plunger and said open-mouthed end of the casing and an elongated weight transmitting member secured to said plunger and extending axially therethrough to project at each end respectively through the mouth and guide means of the casing, the weight transmitting end of said member which projects through said casing mouth being permitted considerable lateral movement to allow for operational requirements whilst the permitted lateral movement of the opposite end of said member is limited by the guide means to an amount substantially equal to that necessary to permit said first-mentioned lateral movement, whereby said plunger and spring are held out of frictional contact with the sides of said casing under normal operating conditions.

2. A spring weighting device as claimed in claim 1 in which said casing is substantially cylindrical and is slit down each side to form two part-cylindrical portions, the said guide means being constituted by a transverse bridge member which joins said two part-cylindrical portions together at one end of the casing and which is formed with a central guide slot, and the said casing mouth being constituted by a bearing plate having a concentric aperture therein, said plate being shaped to retain said two part-cylindrical portions of the casing together at the end remote from said transverse bridge member.

3. A spring weighting device as claimed in claim 2 in which an upstanding annular boss which projects out of the casing defines said concentric aperture in the bearing plate and in which a concentric annular groove is formed in the upper face of said bearing plate around said annular boss for the reception of the down-turned inner ends of inwardly extending projections formed on said part-cylindrical portions of the casing at the mouth end of the latter.

4. A spring weighting device as claimed in claim 1 in which said weight transmitting member is in the form of an elongated flat metal strip which is fixedly connected approximately in the centre to said plunger member and which has its weight transmitting end in the form of a hook.

5. In a drafting mechanism including consecutive pairs of drafting rollers, a saddle assembly for weighting the top rollers of said roller pairs and a roller beam having an aperture therein, a spring weighting device of the kind specified comprising a cylindrical casing having an open mouth at one end and guide means at the opposite end, means for locating said casing beneath said roller beam with the casing mouth in alignment with the aperture in said beam, a plunger arranged loosely within said casing, a coil spring bearing between said plunger and said open-mouthed end of said casing, an elongated weight transmitting member secured to said plunger and extending axially therethrough to project at the lower end through said guide means and at the upper end through the casing mouth and said aperture in the roller beam and means for connecting said upper end of the weight transmitting member to the saddle assembly, the said upper end of the weight transmitting member being permitted considerable lateral movement within the casing mouth and roller beam aperture to allow for operational requirements whilst the permitted lateral movement of the opposite end of said member is limited by the guide means to an amount substan-

tially equal to that necessary to permit said first-mentioned lateral movement, whereby said plunger and spring are prevented from making any frictional contact with the sides of said casing under normal operating conditions.

6. A spring weighting device as claimed in claim 5 in which said casing is formed in two part-cylindrical portions joined at the lower end by a transverse bridge member having a central slot which constitutes said guide means, said locating means including a bearing plate having a concentric aperture therein defined by an up-standing annular boss which is arranged to seat in said aperture in the roller beam.

7. In a drafting mechanism for preparatory and spinning machines having consecutive pairs of drafting rollers and an apertured roller beam, a roller weighting device comprising a cylindrical casing having an open mouth at one end and guide means at the opposite end, means for locating said casing on said machine with said open-mouthed end uppermost and directed towards said drafting rollers, a plunger arranged loosely within said casing, a coil spring bearing between said plunger and said open-mouthed end of the casing and an elongated pull rod secured to said plunger and extending axially therethrough and through said spring to project at each end respectively through the mouth and

guide means of the casing, the upper end of said member which projects through said casing mouth being permitted considerable lateral movement to allow for operational requirements whilst the permitted lateral movement of the opposite end of said member is limited by the guide means to an amount substantially equal to that necessary to permit said first-mentioned lateral movement so that said plunger and spring are held out of frictional contact with the inner wall surface of said casing under normal operating conditions.
